UNITED STATES PATENT OFFICE.

WILLIAM PRELLWITZ, OF EASTON, PENNSYLVANIA, ASSIGNOR TO INGERSOLL-BAND COMPANY, OF NEW YORK, N. Y., A CORPORATION OF NEW JERSEY.

UNLOADER FOR FLUID-COMPRESSORS.

1,027,760.

Specification of Letters Patent.

Patented May 28, 1912.

Application filed March 8, 1911. Serial No. 613,037.

To all whom it may concern:

Be it known that I, WILLIAM PRELLWITZ, a citizen of the United States, and resident of Easton, in the county of Northampton and State of Pennsylvania, have invented a new and useful Improvement in Unloaders for Fluid-Compressors, of which the following is a specification.

This invention relates to improvements in fluid compressors and has for one of its objects the provision of a simple regulating device for controlling the loading and unloading of the pumping mechanism of a compound fluid compressor at successively attained pressures.

Another object is to provide a fluid pressure governed regulator having means such as an auxiliary valve, arranged to successively operate a plurality of main regulator valves which control the loading and unloading of the compressor pumping mechanism.

A still further object is to provide certain improvements in the construction, form, arrangement and operation of the several parts whereby the results are obtained in a simpler and more efficient manner.

A practical embodiment of this invention is represented in the accompanying drawings, in which—

Figure 1 is a top plan view of a duplex compound fluid compressor of the two-stage type with my invention applied thereto, the intercooler and receiver not being shown, Fig. 2 is a side view of the compressor with a portion of the same broken away to more clearly illustrate parts within the same, Fig. 2a is an enlarged detail longitudinal section through one of the auxiliary receiver valves and its adjacent parts, Fig. 3 is an end view of the compressor, Fig. 4 is an enlarged detail view partially in section of my improved regulator, Fig. 5 is a sectional view taken at right angles to Fig. 4, Fig. 6 is a transverse longitudinal central section through the auxiliary valve chest, Fig. 7 is a side view of the same, Fig. 8 is an outer face view of the port plate which is interposed between the auxiliary valve chest and the main valve chest, Fig. 9 is an inner face view of the port plate, and Fig. 10 is a face view of the main valve chest, with the auxiliary valve chest and port plate removed.

I have chosen to illustrate my invention in connection with a duplex compound fluid

compressor of the two stage type, the cylinders of which are provided with auxiliary receivers arranged to be brought into and out of communication with the interiors of their respective cylinders for securing a step by step unloading or loading of the compressor as the fluid in the final receiver reaches successively attained pressures.

The low pressure cylinder is denoted by 1, the high pressure cylinder by 2 and the motor for driving the compressor by 3.

The intercooler is denoted by 4.

The low pressure cylinder 1 is provided with the usual discharge valves 5 and 6 at its inner and outer ends and the high pressure cylinder 2 is provided with the usual discharge valves 7 and 8 at its inner and outer ends. The low pressure cylinder 1 is shown as provided with four auxiliary receivers, the auxiliary receivers 9 and 10 communicating with the inner end of the cylinder and the auxiliary receivers 11 and 12 communicating with the outer end of said cylinder. The high pressure cylinder 2 is shown as similarly provided with four auxiliary receivers, the auxiliary receivers 13, 14, communicating with the inner end of the cylinder and the receivers 15, 16, communicating with the outer end of the said cylinder.

Communication between these several auxiliary receivers and the interiors of the cylinders 1 and 2 is opened and closed by auxiliary receiver valves 17, 18, 19, 20, 21, 22, 23, 24. These auxiliary receiver valves are opened by spring pressure and closed by fluid pressure, in the present instance receiver pressure and in the present instance the regulator for controlling the loading and unloading of these auxiliary receiver valves is shown as arranged to load or unload the pumping mechanism of the compressor in four distinct steps at successively attained pressures, an auxiliary receiver valve upon one side of one cylinder being simultaneously loaded or unloaded with an auxiliary receiver valve upon the opposite side of the other cylinder.

Communication is established between the regulator and the auxiliary receiver valves 17 and 24 through the common pipe 25 and its branches; communication is established between the regulator and the auxiliary receiver valves 19 and 22 through the common pipe 26 and its branches; communication is established between the regulator and the 110

auxiliary receiver valves 18 and 23 through the common pipe 27 and its branches; and communication is established between the regulator and the auxiliary receiver valves 20, 21, through the common pipe 28 and its branches. Each auxiliary receiver valve is constructed as shown in detail in Fig. 2^a, the valve stem 29 being provided with a piston 30 fitted to slide in a chamber 31, which chamber is brought into and out of communication with fluid pressure, in the present instance the receiver pressure, by the regulator to be hereinafter specifically described. One or more springs 32 serve to open the valve when fluid pressure is removed from the chamber 31. The auxiliary receiver valves are thus positively opened and closed.

I will now proceed to describe the fluid pressure governed regulator for loading and unloading the auxiliary receiver valve as different successively attained pressures are reached. The main valve chest 33 of the regulator is provided with four main regulator valves 34, 35, 36, 37, having double headed pistons 38, 39, 40, 41, respectively. The spaces between the heads of the several pistons are at all times open to receiver pressure through ports 42, 43, 44, 45, opening into a common port 46 in the port plate 47 which port 46 is connected to a pipe 48 leading from the receiver not shown herein. The main regulator valve ports 49, 50, 51, for the valves 33, 36, 37, are at all times in open communication with the common port 52, which port 52 is at all times in open communication with external atmosphere through the port 53 of the chamber 54 in the base of the valve chest 33. The valve port 55 of the valve 34 opens directly into the said chamber 54. The pipes 25, 26, 27, 28, are provided with main regulator valve ports 56, 57, 58, 59, controlled by the main regulator valves, 34, 35, 36, 37, respectively. These main regulator valves are provided with bridge ports 60, 61, 62, 63. When these main regulator valves are at the limits of their movements in one direction the ports 56, 57, 58, 59, will be open to receive pressure thus throwing the load onto the auxiliary receiver valves 17, 18, 19, 20, 21, 22, 23, 24. When the main regulator valves are at the limits of their movements in the other direction the several ports 56, 57, 58, 59, will be brought into open communication with external atmosphere through the bridge ports 60, 61, 62, 63, and ports 55, 49, 50, 51, respectively, thus unloading the auxiliary receiver valves above referred to.

Any suitable means may be employed for operating the several main regulator valves at successively attained pressures so as to load or unload the pumping mechanism step by step, which means is shown, in the present instance, as constructed, arranged

and operated as follows: A chamber 66 is provided in the top of the main valve chest 33, which chamber is at all times open to receiver pressure through the passage 67. This chamber is provided with a flexible diaphragm 68, which diaphragm receives the weight of a lever 69 through connecting pieces 70, 71. This lever 69 is pivoted at 72 on the top 73 of the main valve chest 33. A graduated resistance is provided for the lever 69, which resistance is herein shown as a series of weights 74 adjustable along the lever 69 combined with a spring resistance including a spring holder 75, a depending rod 76, a lever stop 77 adjustable on said rod within the holder 75 and a spring 78 interposed between the holder 75 and the stop 77. This weighted lever 69 operates the means which controls the movements of the main valves, which means, in the present instance, is shown as an auxiliary valve 79 fitted to slide within the auxiliary valve chest 80. This auxiliary valve is shown herein as a spool valve and it is moved longitudinally back and forth within the chamber 81 by the lever 69 through a valve rod 82 and link 83. The inner end of a valve guide screw 84 enters a longitudinally elongated slot 85 in the auxiliary valve 79 for preventing the valve from turning. The chamber 81, beyond the heads 86, 87, of the auxiliary valve, is at all times in open communication with external atmosphere through passages 88, 89, leading to the common port 52 hereinbefore referred to. The receiver pressure is admitted to the space around the reduced body portion of the auxiliary valve between its heads 86, 87, through a passage 90, said reduced body portion forming a bridge port. The inner wall 105 of the auxiliary valve chest 80 is provided with through ports 91, 92, 93, 94, which are in open communication by means of passages 95, 96, 97, 98, in the port plate 47, with ports 99, 100, 101, 102, at the corresponding ends 110 of the main regulator valve pistons 38, 39, 40, 41. The inner wall of the auxiliary valve chest 80 is also provided with through ports 103, 104, 105, 106, which are in open communication by means of passages 107, 108, 115 109, 110, in the port plate 47, with ports 111, 112, 113, 114, on the opposite side of the main regulator valve pistons 38, 39, 40, 41. The operation of the fluid pressure governed regulator is as follows: When the 120 parts are in their normal position shown in the accompanying drawings, with the auxiliary valve 79 at the limit of its downward movement, the ports 91, 92, 93, 94, and thereby the ports 99, 100, 101, 102, will be open 125 to external atmosphere; and the ports 103, 104, 105, 106, and thereby the ports 111, 112, 113, 114, will be opened to receiver pressure. The main regulator valves 34, 35, 36, 37, will thus be held at the limits of their move- 130

ments in a direction which will open the several auxiliary receiver valves to receiver pressure and thus hold the said auxiliary receiver valves closed and the pumping mechanism of the compressor loaded. As the receiver pressure begins to rise it will act upon the diaphragm 68 thus raising the lever 69. When the lever has been raised a predetermined distance, the auxiliary valve 79 will have been moved into a position to open the port 91 and thereby the port 99 to receiver pressure and at the same time open the port 103 and thereby the port 111 to external atmosphere. This condition will cause the main regulator valve 34 to be moved to the limit of its movement in the other direction thus unloading the auxiliary receiver valves 17, 24, upon opposite sides of the low and high pressure cylinders, by removing the receiver pressure from their pistons 30 and permitting their springs 32 to open the said valves. If the receiver pressure still continues to rise after this partial unloading of the pumping mechanism, the next set of auxiliary receiver valves 19, 22, will be unloaded. A still further rise in pressure will unload the auxiliary receiver valves 18, 23, and a still further rise in receiver pressure will unload the auxiliary receiver valves 20, 21. A fall in receiver pressure will successively load the said pairs of auxiliary receiver valves at successively attained pressures until the pumping mechanism is fully loaded.

While I have shown and described a mechanism for loading and unloading a fluid compressor in four steps I do not wish to be limited to any particular number of steps.

It will be seen that by the mechanism herein shown and described I am enabled to load and unload a compound fluid compressor by a device controlled only by variations in the receiver pressure without the more complex piping and connections required where intercooler pressure is also utilized.

Attention is called to my copending applications filed November 20, 1908, Serial Nos. 463,603 and 463,604, which are directed to the loading and unloading of both single and compound fluid compressors by a single fluid pressure governed regulator arranged to unload and load the valves of auxiliary receivers as the receiver pressure rises and falls; as distinguished from this present application which is directed to combinations which include means for positively opening the auxiliary receiver valve combined with pressure fluid operated means for closing the said valve and to combinations with compound fluid compressors of means for connecting said pressure fluid operated means either to receiver pressure or to atmosphere.

It is evident that various changes might be resorted to in the form, construction and

arrangement of the several parts without departing from the spirit and scope of my invention; hence I do not wish to limit myself strictly to the structure herein set forth, but

70

What I claim is:

1. The combination with the cylinder of a fluid compressor, of an auxiliary receiver, a valve connecting the cylinder and auxiliary receiver, pressure fluid operated means for closing said valve, means for positively opening said valve and means for connecting said pressure fluid operated means either to receiver pressure or to atmosphere.

75

2. The combination with the cylinder of a fluid compressor, of an auxiliary receiver, a valve connecting the cylinder and auxiliary receiver, pressure fluid operated means for closing said valve, means for positively opening said valve and fluid pressure controlled means for connecting said pressure fluid operated means either to receiver pressure or to atmosphere.

80

3. The combination with the cylinder of a fluid compressor, of an auxiliary receiver, a valve connecting the cylinder and auxiliary receiver, pressure fluid operated means for closing said valve, a spring for positively opening said valve and means for connecting said pressure fluid operated means either to receiver pressure or to atmosphere.

85

4. The combination with the cylinder of a fluid compressor, of an auxiliary receiver, a valve connecting the cylinder and auxiliary receiver, pressure fluid operated means for closing said valve, a spring for positively opening said valve and fluid pressure controlled means for connecting said pressure fluid operated means either to receiver pressure or to atmosphere.

90

5. The combination with the cylinder of a fluid compressor, of an auxiliary receiver, a valve connecting the cylinder and auxiliary receiver, said valve having a pressure fluid operated piston, means for positively opening the valve and means for connecting said piston either to receiver pressure or to atmosphere.

105

6. The combination with the high and low pressure cylinders of a compound fluid compressor, of auxiliary receivers, valves for opening and closing communication between the cylinders and their auxiliary receivers and a regulator arranged to open the auxiliary receiver valves of both the high and low pressure cylinders either to receiver pressure or to atmosphere.

110

7. The combination with the high and low pressure cylinders of a compound fluid compressor, of auxiliary receivers, valves for opening and closing communication between the cylinders and their auxiliary receivers and a regulator comprising a plurality of main valves arranged to open the auxiliary receiver valves of both the high

115

120

125

130

and low pressure cylinders either to receiver pressure or to atmosphere and means for controlling the movements of said main regulator valves.

8. The combination with the high and low pressure cylinders of a compound fluid compressor, of auxiliary receivers, valves for opening and closing communication between the cylinders and their auxiliary receivers and a regulator comprising a plurality of main valves arranged to open the auxiliary receiver valves of both the high and low pressure cylinders either to receiver pressure or to atmosphere, and fluid pressure operated means for controlling the movements of the said main regulator valves.

9. The combination with the high and low pressure cylinders of a compound fluid compressor, of auxiliary receivers, valves for opening and closing communication between the cylinders and their auxiliary receivers and a regulator comprising a plurality of main valves arranged to open the auxiliary receiver valves of both the high and low pressure cylinders either to receiver pressure or to atmosphere and a single auxiliary valve for controlling the movements of the said main regulator valves.

10. The combination with the high and low pressure cylinders of a compound fluid compressor, of auxiliary receivers, valves for opening and closing communication between the cylinders and their auxiliary receivers and a regulator comprising a plurality of main valves arranged to open the auxiliary receiver valves of both the high and low pressure cylinders either to receiver pressure or to atmosphere and a fluid pressure operated lever for moving the auxiliary valve.

11. The combination with the high and low pressure cylinders of a compound fluid compressor, of auxiliary receivers for the low pressure cylinder, valves for opening and closing communication between the low pressure cylinder and its auxiliary receivers and a regulator arranged to open said auxiliary receiver valves either to receiver pressure or to atmosphere.

12. The combination with the high and low pressure cylinders of a compound fluid compressor, of auxiliary receivers for the low pressure cylinder, valves for opening and closing communication between the low pressure cylinder and its auxiliary receivers and a regulator comprising a plurality of main valves arranged to open the auxiliary receiver valves either to receiver pressure or to atmosphere and means for controlling the movements of the said main valves.

13. The combination with the high and

low pressure cylinders of a compound fluid compressor, of auxiliary receivers for the low pressure cylinder, valves for opening and closing communication between the low pressure cylinder and its auxiliary receivers and a regulator comprising a plurality of main valves arranged to open the auxiliary receiver valves either to receiver pressure or to atmosphere and fluid pressure operated means for controlling the movements of the said main valves.

14. The combination with the high and low pressure cylinders of a compound fluid compressor, of auxiliary receivers for the low pressure cylinder, valves for opening and closing communication between the low pressure cylinder and its auxiliary receivers and a regulator comprising a plurality of main valves arranged to open the auxiliary receiver valves either to receiver pressure or to atmosphere and a single auxiliary valve for controlling the movements of the said main valves.

15. The combination with the high and low pressure cylinders of a compound fluid compressor, of auxiliary receivers for the low pressure cylinder, valves for opening and closing communication between the low pressure cylinder and its auxiliary receivers and a regulator comprising a plurality of main valves arranged to open the auxiliary receiver valves either to receiver pressure or to atmosphere and a fluid pressure operated lever for moving the auxiliary valve.

16. The combination with the high and low pressure cylinders of a compound fluid compressor, of auxiliary receivers therefor, auxiliary receiver valves, a common source of fluid pressure for said auxiliary receiver valves, and a regulator having respectively a port communicating with an auxiliary receiver valve of each cylinder, a fluid pressure supply port, and an exhaust port to external atmosphere, a main valve and means for controlling the movements of the said main valve for opening said auxiliary receiver valves either to fluid pressure or to atmosphere for loading and unloading said auxiliary receiver valves.

17. The combination with the high and low pressure cylinders of a compound fluid compressor, of auxiliary receivers therefor, auxiliary receiver valves and a regulator having respectively a port communicating with an auxiliary receiver valve of each cylinder, a receiver pressure supply port, and an exhaust port to external atmosphere, a main valve and means for controlling the movements of the said main valve for opening said auxiliary receiver valves either to receiver pressure or to atmosphere for loading and unloading said auxiliary receiver valves.

18. The combination with the high and

low pressure cylinders of a compound fluid compressor, of auxiliary receivers therefor, auxiliary receiver valves, a common source of fluid pressure for said auxiliary receiver valves, a regulator comprising a plurality of main valves each having a port communicating with an auxiliary receiver valve of each cylinder, a fluid pressure supply port and an exhaust port to external atmosphere 10 and means for controlling the movements of the said valves whereby the auxiliary receiver valves may be opened to fluid pressure or to external atmosphere for loading and unloading said auxiliary receiver valves.

19. The combination with the high and low pressure cylinders of a compound fluid compressor, of auxiliary receivers therefor, auxiliary receiver valves, a regulator comprising a plurality of main valves each having a port communicating with an auxiliary receiver valve of each cylinder, a receiver pressure supply port, and an exhaust port, to external atmosphere and means for controlling the movements of the said valves whereby the auxiliary receiver valves may be opened to receiver pressure or to external atmosphere for loading and unloading said auxiliary receiver valves.

20. The combination with the high and low pressure cylinders of a compound fluid compressor, of auxiliary receivers for the low pressure cylinder, auxiliary receiver valves and a regulator comprising a plurality of main valves each having an auxiliary receiver valve port, a receiver pressure supply port and an exhaust port to atmosphere, and means for controlling the movements of the said main valves for opening the auxiliary receiver valves either to receiver pressure or to atmosphere for loading and unloading said valves.

low pressure cylinder, auxiliary receiver valves and a regulator having respectively an auxiliary receiver valve port, a receiver pressure supply port and an exhaust port to atmosphere, a main valve and means for controlling the movements of the main valve to open the auxiliary receiver valve either to receiver pressure or to atmosphere for loading and unloading said auxiliary receiver valve.

21. The combination with the high and low pressure cylinders of a compound fluid compressor, of auxiliary receivers for the low pressure cylinder, auxiliary receiver valves and a regulator comprising a plurality of main valves each having an auxiliary receiver valve port, a receiver pressure supply port and an exhaust port to atmosphere, and means for controlling the movements of the said main valves for opening the auxiliary receiver valves either to receiver pressure or to atmosphere for loading and unloading said valves.

In testimony, that I claim the foregoing as my invention, I have signed my name in presence of two witnesses, this twenty-fourth day of February 1911.
